described and within the scope of the appended claims.

Having described the invention, what is claimed as new is:

1. A holder for retaining open safety pins comprising a container having a heart-shaped end wall, arcuate side walls secured to the end wall having bottom edges spaced from the bottom edge of the side wall, and a rear wall of the same length as the side walls secured to the latter, partitions in said container dividing the latter into separate compartments, and means carried by the rear wall for attaching said container to a garment, the open safety pins being retained in

said compartments with their coiled ends extending below the bottom edges of said side walls.

2. The combination of claim 1 wherein said means includes a clip and a fastening pin received in said clip.

3. The combination of claim 1 and means for shielding the open end of the safety pins, said means including inwardly arcuated extensions carried by the upper ends of said side walls.

10 4. The combination of claim 3 wherein said means includes a clip and a fastening pin received in said clip.

HELEN S. COHEN.
